UNITED STATES PATENT OFFICE.

PETER SCHIFFLER, OF AACHEN, GERMANY, ASSIGNOR TO MATHIAS SCHIFFLER, OF AACHEN, GERMANY.

PILE-PLANKING OF ROLLED IRON.

1,085,493.

Specification of Letters Patent.

Patented Jan. 27, 1914.

Application filed September 26, 1912. Serial No. 722,506.

To all whom it may concern:

Be it known that I, PETER SCHIFFLER, engineer, a subject of the King of Prussia, residing at No. 10 Stephanstrasse, Aachen, in 5 the Kingdom of Prussia, Empire of Germany, have invented certain new and useful Improvements in Pile-Planking of Rolled Iron; and I do hereby declare the following to be a full, clear, and exact description 10 of the invention, such as will enable others skilled in the art to which it appertains to make and use the same.

My present invention relates to improvements in a pile-planking of rolled iron such 15 as described in the specification of an application filed by me and bearing the date of September 24th 1912, Serial No. 722,115, and the invention consists in that between the two guiding places lying in the neutral 20 axis of the planking, there are in each plank two full slanting walls arranged, whereas in the application Serial No. 722,115 only one slanting wall is formed between the said places, so that in a finished pile-planking 25 according to the present invention, one slanting wall interrupted by a guide is followed by two non-interrupted or full slanting walls. By this means the rolling of the plank is especially simplified.

30 The plank sections of the application Serial No. 722,115, represented in Figures 1 and 2 of the annexed drawings, are so manufactured as to have the X—X axis of the sections lying parallel with the horizontal 35 axis of the rollers. When such sections or profiles have left one tap-hole and are carried off by the rolling track of the rolling train, in order to be conducted into the next following narrower groove, difficulties are 40 experienced on bringing the section in alignment with the following groove, as the section has, on account of its cross-section form, the disposition to tilt on the roller path or track and to take the position shown in 45 Fig. 3, whereby the X—X axis comes into a gradient toward the axis of the rollers. It is therefore difficult to conduct the section into the next groove, because for this purpose the X—X axis of the section must 50 be brought into parallel position to the axis of the rollers, which requires a turning of the rolled bar to about 45° this being connected with great efforts. This disadvantage caused by the necessary supplementary work is according to the present invention 55

removed by two full slanting walls being provided for between the slanting half walls which have guides at their ends, in each section or profile. On account of this arrangement the section is set on the roller path or 60 track with two surfaces, and therefore the X—X axis remains in parallel situation with reference to the axis of the rollers, so that the section, in order to be brought into engagement with the next following groove, 65 has only to be elevated but not to be turned. By this, the costs of manufacturing the planks are reduced.

In Figs. 5—8 pile-plankings are represented which are composed of planks, being 70 formed according to the present invention, each of which planks is provided with two uninterrupted full slanting walls. Thus the section of each plank has approximately the shape of a W, as will be understood from 75 Figs. 4—6. According to Fig. 5 the pile-planking may be composed of planks having the same section, which at one edge or end has an enlargement and at the other one a corresponding guiding groove adapted to 80 receive such an enlargement, or the planking may be constructed, as represented in Fig. 6, of two different sections which are arranged alternately. In the latter case one section is provided on both edges with 85 enlargements, while the other section possesses on both edges guiding grooves.

The Figs. 7 and 8 represent top views of pile-plankings to which the inventor's idea with the Z-shaped sections of the application Serial No. 722,115 has been applied. 90 Also here the planking can be composed of planks of the same section (Fig. 7) or of alternating planks having two different sections (Fig. 8). Each of the planks comprises an approximately Z-shaped body portion 5. Carried by this body portion are the means for interlocking the planks to form a structure. Upon one end of the plank is formed a peculiarly shaped head 6, provided with an outwardly flaring shoulder 7. This head 6, is adapted to be inserted into a pocket 8, carried by another one of the planking units. This socket is formed to make a sliding fit for the head 6, and is provided with an inwardly turned member 9, which engages the shoulder 7, on the head 6. These interlocking portions of the planking units are placed at the the abutting ends of the planking units. The units may be provided with two sockets, 110

one at each edge, or they may be provided with two heads or a head and a socket as desired. These units are slid one into the other, the socket of one member receiving the head of the other member.

Having thus described my invention, what I claim is:—

A metallic sheet piling, comprising detachable planking units, each unit comprising a plurality of relatively long sections angularly disposed with relation to each

other, oppositely bent relatively short sections carried by said longer sections, and means carried by said shorter sections adapted to secure adjacent planking units.

15

In testimony whereof I have signed my name to this specification in the presence of two subscribing witnesses.

PETER SCHIFFLER.
